CLAIM

The ornamental design for a display screen or portion thereof with graphical user interface and icon, as shown and described.

DESCRIPTION

FIG. 1 is a front view of our design for a display screen or portion thereof with graphical user interface and icon; and, FIG. 2 is an enlarged front view taken from the broken line box marked “2” of FIG. 1.

The outer broken line rounded rectangle in FIG. 1 shows an electronic device that forms no part of the claimed design. The inner broken line rounded rectangle in FIG. 1 shows the display screen or portion thereof, the broken line square box in FIG. 1 marks the area “2” for an enlarged detailed view in FIG. 2, and all other broken lines show portions of the graphical user interface. The broken lines form no part of the claimed design.
